Specification for Design.

Patented Oct. 18, 1921.

Application filed December 17, 1920. Serial No. 431,487. Term of patent 7 years.

To all whom it may concern:

Be it known that I, JOHN A. MACMILLAN, a citizen of the United States, residing at Dayton, in the county of Montgomery, State of Ohio, have invented a new, original, and ornamental Design for a Non-Skid Tread for Airless or Pneumatic Tires, of which the following is a specification, reference being

had to the accompanying drawing, forming part thereof.

The figure is an oblique projection view of a tire showing my new design.

I claim:

The ornamental design for a non-skid tread for airless or pneumatic tires as shown.

JOHN A. MACMILLAN.
